UNITED STATES PATENT OFFICE.

CHARLES E. EMERY, OF BROOKLYN, NEW YORK.

STEAM-TABLE.

SPECIFICATION forming part of Letters Patent No. 323,570, dated August 4, 1885.

Application filed September 27, 1884. (No model.)

To all whom it may concern:

Be it known that I, CHARLES E. EMERY, a citizen of the United States, and a resident of the city of Brooklyn, county of Kings, and State of New York, have invented a new and useful Improvement in Steam-Tables, of which the following is a specification.

My invention relates to the construction of steam-tables; and it consists of a chambered or hollow table, at least one plate of which, preferably the bottom, is formed of a series of inverted arches, and is connected with the other plate, which may be constructed with arches or in any customary manner, by a series of studs or ribs at the springings of the arches; and it further consists of a cross-channel connecting the chambers for drainage.

Reference is had to the accompanying drawings, forming part of this specification, in which similar letters of reference indicate similar parts, and in which Figure 1 is an elevation, partly in view and partly in section, at right angles to the lines of the inverted arches, and passing partly through the center of the cross-drainage channel and drip-pipe. Fig. 2 is an elevation at right angles to the elevation in Fig. 1, partly in view and partly in section.

The table, as shown, is to be cast in one piece, with a series of connecting-chambers. The top A, as shown, is a plain plate strengthened internally by ribs a^2 . The bottom plate, B, is formed of a series of inverted arches, b^2 .

Ribs or studs a^3 form stays to connect the springings of the arches b^2 with the top plate. 35 Transversely to the arches b^2 runs a channel, b^3 , which connects the bottoms of the arches b^2 , for the purpose of draining the water of condensation from the arches and carrying it to the drip-pipe G. Openings d' through the 40 ribs a^3 , together with the channel b^3 , afford free passage for the steam to all parts of the interior of the table.

When the bottom plate of a steam-table is made plain and ribbed, it is difficult to be assured that the openings through the ribs are all clear without making them so large as to reduce the strength. The series of connected arches gives the requisite strength without the use of small connecting-openings. 50

Having thus fully described my invention, what I claim as new, and desire to secure by Letters Patent, is—

1. A chambered heating-table, of which at least one plate is constructed of a series of arches, and is connected to the other plate by stays, substantially as specified.

2. A chambered heating-table provided with an arched lower plate and a cross-channel connecting bottoms of arches, substantially as and for the purposes set forth.

CHAS. E. EMERY.
